UNITED STATES PATENT OFFICE.

GEORGE IRA HERRICK, OF WHEATON, ILLINOIS.

PLATE FOR MAKING STENCIL-SHEETS.

SPECIFICATION forming part of Letters Patent No. 776,180, dated November 29, 1904.

Application filed February 2, 1904. Serial No. 191,670. (No model.)

To all whom it may concern:

Be it known that I, GEORGE IRA HERRICK, a citizen of the United States, residing at Wheaton, in the county of DuPage and State 5 of Illinois, have invented new and useful Improvements in Plates for Making Stencil-Sheets, of which the following is a specification.

My invention relates to stencil-plates, and 10 more particularly to that kind of stencil-plates which are used in making autographic stencils for the reproduction of drawings containing circles, radii, and tangents to circles by the mimeographic process, the special object of this invention being to form a plate 15 for making stencil-plates with spiral grooves thereon.

Heretofore with stencil-plates that have been engraved or stamped with a series of 20 straight lines it has been difficult to draw circles and their radii, owing to the fact that at four points upon the circumference of a circle there will be points of tangency to the 25 grooves of a plate engraved with a double series of straight lines, and there will be four radii, the drawing of which is impossible with a straight-line-grooved plate, since the stylus will follow in these grooves and cause the 30 ruination of the stencil-paper.

The present invention is for the purpose of 35 avoiding this difficulty and making it possible to draw circles, radii to circles, and tangents to circles with ease and facility, the plate being engraved with spirals and so constructed 40 that no circle which is larger than the inner circle of the plate will have points of tangency to any groove.

The advantages and the structure of the 45 stencil-plate will appear more particularly in the following detailed description and may be seen upon reference to the accompanying drawings, in which—

Figure 1 is a plan view of the stencil-plate. Fig. 2 is a section on spirals A A' and B B' 50 before the spirals D A' and C B' are got. Fig. 3 is a section on spirals A A' and B B' after the getting of spirals D A' and C B' and others, including supplementary spirals. Fig. 4 is a section of the plate on line G G'.

Referring more particularly to the draw-

ings, P is a stencil-plate consisting of a flat piece of metal upon which is engraved or stamped spiral curves—such as A A', B B', C B', D A', and others. One end of each of said curves is tangent to the inner circle H, 55 each spiral being placed upon the plate as a radial spiral. The inner circle H includes a soft piece of wood or horn, which provides a suitable material upon which to place the needle-point of a compass, which is illustrated 60 and indicated at p. If it is so desired, the interior of the circle H may also be provided with spirals; but it is preferable in actual use to provide the interior of the circle with the material described. 65

On account of the fact of the outer end of the spirals A, B, C, and D occupying a larger angular opening than at the inner portion near the circle H supplementary spirals, before referred to, are provided, which are practically 70 parallel to the original spirals—as, for instance, A A'—but which extend only a portion of the distance and give the effect indicated at E, which will result in there being a series of fine radial spirals cut in the plate at 75 certain fixed distances apart, according to the proportions of the original spiral. When the same operation is gone through with the spirals D, A', and others, a similar effect is gotten, as illustrated and referred to above 80 and indicated at F.

The result of this is a series of spirals and supplementary spirals crossing each other, as shown at F, and produces the effect upon the plate of a number of small diamonds, which are, as is readily understood, of extremely small area after the division of the plate in the manner before described. The manner of using this plate as provided with these spiral grooves cut into the face of the same is the ordinary process 90 common in the art of mimeographing and consists simply in placing a slab of soft paper or other material upon the plate and the drawing, for instance, to be reproduced upon the soft paper, the lines thereof being made by a 95 person using a stylus. The result as due to the present invention is that curves of all natures may be easily reproduced, due to the different circles possible to be made and the tangents and radii thereof which can be easily 100

drawn. This result is new, as has been before stated, since it has only been possible heretofore to reproduce straight lines with any accuracy and surety.

5 Therefore what I claim, and desire to secure protection on by Letters Patent, is as follows:

1. As a new article of manufacture, a plate for producing a stencil-sheet having its face 10 provided with a plurality of spiral grooves radiating from a common central circle, substantially as set forth.

2. A plate for producing a stencil-sheet having a series of substantially parallel spiral 15 grooves formed in the face thereof radiating from the center of the plate, whereby circles and their curves may be reproduced by a mimeographic process, substantially as set forth.

3. A plate for making stencil-sheets comprising a body portion having a series of spi- 20

ral parallel grooves formed in the face thereof and a central circle from which said grooves radiate, substantially as described.

4. A stencil-plate of the type set forth having a central inner circle provided with a soft 25 material within the same, and a series of intersecting spiral grooves formed in the face of the plate and radiating from said circle.

5. A plate for producing stencil-plates comprising a series of intersecting spiral grooves 30 formed in the face of the plate and radiating from a central circle within the plate, substantially as described.

In testimony whereof I have signed my name to this specification in the presence of two sub- 35 scribing witnesses.

GEORGE IRA HERRICK.
